UNITED STATES PATENT OFFICE

122,456

DESIGN FOR A CASING FOR ELECTRICAL HEATING PADS

William Bradford, Taunton, Mass.

Application April 5, 1940, Serial No. 91,487

Term of patent 14 years

To all whom it may concern:

Be it known that I, William Bradford, a citizen of the United States, residing at Taunton, in the county of Bristol and State of Massachusetts, have invented a new, original, and ornamental Design for a Casing for Electrical Heating Pads, of which the following is a specification, reference being had to the accompanying drawing, forming a part thereof.

Referring to the drawing:

Fig. 1 is a side elevational view of a casing for electrical heating pads showing my new design; and

Fig. 2 is a plan view of the same.

The essential features of the design reside in a casing for electrical heating pads having concaved opposed edge portions, symmetrical with the major axis of the casing which connect substantially semi-circular ends, one of said ends having a cord receiving portion of the specific configuration shown.

I claim:

The ornamental design for a casing for electrical heating pads, as shown and described.

WILLIAM BRADFORD.
